Attorney

UNITED STATES PATENT OFFICE.

CHARLES J. SCHMIDT, OF EVANSTON, ILLINOIS.

RECEPTACLE.

No. 873,797.

Specification of Letters Patent.

Patented Dec. 17, 1907.

Application filed January 10, 1907. Serial No. 351,585.

To all whom it may concern:

Be it known that I, CHARLES J. SCHMIDT, a citizen of the United States, residing at Evanston, in the county of Cook and State of Illinois, have invented a certain new and useful Improvement in Receptacles, of which the following is a full, clear, concise, and exact description, reference being had to the accompanying drawings, forming a part of this specification.

My invention relates to receptacles, and its object is to provide improved means for facilitating the opening thereof.

My invention is particularly adaptable to receptacles for containing shoe blacking, stove blacking, salve, pills, tape and so on. These receptacles or boxes, particularly for containing shoe blacking, are sometimes extremely difficult to open in the natural way, the blacking and sometimes the varnish with which the box is coated, getting under the rim of the cover and practically gluing it to the receptacle body. Various means have been devised for opening such boxes, but these means are all in the nature of mechanical attachments which sometimes cost more than the box itself, therefore, making the use of the box prohibitive as a commercial article. My invention on the other hand is extremely simple as well as efficient, and does not in the least increase the cost of manufacture.

Broadly, my invention consists in providing an opening through one of the box parts, such opening having an edge in line with the edge of the other part when the box is closed, the adjacent edges leaving a thin slit through which the blade of a knife may be pushed or wedged to force open the box.

In the accompanying drawing my invention and various modifications are shown.

Figure 1 is a plan view of a box to which my invention is applied; Fig. 2 is a front view of the box; Fig. 3 is a sectional view taken on line 3—3 of Fig. 2; Fig. 4 is a front view of part of a box, showing a modified arrangement of my invention; Fig. 5 is a sectional view taken on line 5—5 of Fig. 4; Fig. 6 is a front view of a part of a box, showing another modified form of my invention; Fig. 7 is a sectional view taken on line 7—7 of Fig. 6; Fig. 8 is an interior view of the body part of the box shown in Fig. 7, and Fig. 9 is an interior view of the cover part of the box shown in Fig. 7.

My various modifications of the invention

are shown in the figures applied to cylindrical boxes, such as a shoe blacking box, having the body part *b* and the cover part *c*. The body part has the bead *a* engaged by the edge *d* of the cover part when the box is closed.

Figs. 2 and 3 show perhaps the simplest form of my invention. The blank from which the cover is formed is punched to leave a rectangular opening *o* which appears in the cylindrical wall *e* when the cover is completed and in such position that its upper edge *f* is substantially in line with the edge *g* of the body part when the cover engages the body part so that a thin slit *s* is provided through which a knife blade or other suitable instrument may be pushed or wedged to thereby force the cover from the body part to open the box. The height of the opening *o* may be sufficient so that the inserted blade may be turned when between the edges *f* and *g*. The section *h* below the opening *o* prevents spreading of the cover when applied which spreading would otherwise happen with the opening *o* extended to the edge *d* of the cover.

The slit *s* is so thin that the contents of the box will be in no great danger of evaporation, but where it is particularly desired that any evaporation be guarded against, varnish or other suitable substance may be daubed over the slit, the box being then rendered absolutely air tight. A paster *p* may also be applied over the opening *o* and the slit after the box is closed. This paster may be of transparent material so that the slit can be seen, or a black line or other designating means may appear on the paster to show where the slit is, and directions for opening the box may also be printed on the paster.

In Figs. 4 and 5 is shown a modified arrangement. Here the opening *o* appears in the cylindrical wall *r* of the body part and in such position that its lower edge *l* is substantially in line with the edge *d* of the cover when the box is closed, and with this arrangement the slit *s* will appear below the edge *d* as shown, and upon insertion of a knife blade the cover may readily be wedged from the body part. To render the box air tight with this arrangement, the preferable way would be to apply varnish or other suitable substance to fill the slit.

The arrangement shown in Figs. 2 and 3 is best adapted for receptacles which are to contain plastic substances, such as shoe pol-

ish, stove polish, salve, etc., as the body part can be completely filled to its upper edge, there being no danger of leakage through the opening *o*.

5 In the arrangement shown in Figs. 4 and 5, there might, however, be leakage through the opening *o* if the contents of the box were plastic, and this form of box, therefore, is better adapted for containing solid material 10 like pills, tape, etc.

In Figs. 6, 7, 8 and 9 is shown another modification which might be better adapted for larger boxes which require more force to open them. In this arrangement the cover 15 is formed with a tongue *t* extending inwardly from the edge *f* of the opening *o*, the lower face of this tongue lying in the plane of the edge *g* of the body part. The body part of the box is also formed with a tongue *u* extending inwardly from its upper edge with 20 its upper face in the plane of the edge so that when the cover is applied, the tongues *t* and *u* will closely engage each other, as shown in Fig. 7. The edges *f* of the tongue *t*, and *j* of the tongue *u* are slightly rounded, thus allowing ready entrance of the knife blade between 25 the tongues. These tongues strengthen the edges *f* and *g* where the knife blade is inserted, and besides by closely engaging prevent 30 evaporation through the opening *o*. Varnish or other suitable substance, however may also be daubed to fill the opening *o* and the entrance slit to insure air tightness, or a 35 paster might also be applied over the opening. Where the box contains plastic material, such as shoe blacking, some of the substance may be applied to the tongue *u* so that when the cover is applied, this substance will 40 form a packing about the opening, thus to make the box air tight. The tongues *t* and *u* may also be so placed that their engaging 45 faces lie in a plane below or above the edge *g* of the body part.

Both parts of the box of my invention may 45 be stamped integral from sheet material.

The form of my invention applied as shown in Figs. 2 and 3 does not in the least increase the cost of manufacture. Even with the additional tongues *u* and *t*, the manufacture 50 price will not be materially increased. At the same time the box can be easily opened and without injury to the knife blade when a knife is used. In some boxes on the market, the directions are to run the point of a knife 55 under the edge of the cover, but in so doing the knife is injured and besides the cover will be on just as tight after as before.

I do not wish to be limited to the construction and modifications here shown, as more 60 modifications will suggest themselves.

I claim broadly new the feature of having an opening through one of the box members which opening has an edge coming in line with an edge in the other member to form a 65 thin slit when the box is closed, said thin slit

allowing the insertion of a knife blade or other suitable implement by means of which the box members may be forced apart.

I, therefore, desire to secure by Letters Patent the following claims:

1. In a receptacle comprising a body member and a cover member, said members having telescoping walls, an opening through one wall within the edge thereof so as to leave the edge intact, one edge of the opening being opposite an edge on the other wall whereby a suitable implement may be inserted between the opposite edges to force the members apart. 75

2. In a receptacle comprising a body member and a cover member, said members having telescoping walls, an opening through one wall within the edge thereof so as to leave the edge intact, one edge of the opening being opposite an edge on the other wall whereby a suitable implement may be inserted between the opposite edges to force the members apart, and sealing means for the opening through which sealing means the opening implement may readily be passed. 80

3. In a receptacle, the combination with a body member having a horizontal and a vertical wall, of a cover member having a horizontal wall and a vertical wall for engaging the vertical wall of the body member to close 95 the receptacle, there being a rectangular opening through the vertical wall of one member inside the edge thereof to leave the edge intact, one edge of the rectangular opening being substantially in line with the outer 100 edge of the other member to provide a thin entrance slit into the receptacle when the members are engaged to close the receptacle whereby a knife blade or other implement may be inserted into the box between the 105 opposed edges of the slit to force the receptacle members apart.

4. In a receptacle, the combination with a body member having a horizontal and a vertical wall, of a cover member having a horizontal wall and a vertical wall for engaging the vertical wall of the body member to close the receptacle, there being a rectangular opening through the vertical wall of one member inside the edge thereof to leave the 115 edge intact, one edge of the rectangular opening being substantially in line with the outer edge of the other member to provide a thin entrance slit into the receptacle when the members are engaged to close the receptacle whereby a knife blade or other implement may be inserted into the box between the 120 opposed edges of the slit to force the receptacle members apart, and sealing material applied over the slit when the box is closed through which sealing material the knife blade or other implement may easily be passed. 125

5. A receptacle comprising a body part and a cover part, each having a horizontal 130

and a vertical wall, there being a rectangular opening through the vertical wall of the cover part within the edge thereof to keep the edge intact, the upper edge of which opening is adapted to appear opposite and substantially coincident with the upper edge of the body member when the receptacle is closed, thereby providing a thin slit through which a knife blade or other implement may be inserted into the receptacle for forcing the members apart.

6. A receptacle comprising a body part and a cover part, each having a horizontal and a vertical wall, there being a rectangular opening through the vertical wall of the cover part within the edge thereof to keep the edge intact, the upper edge of which opening is adapted to appear opposite the upper edge of the body member when the receptacle is closed, thereby providing a thin slit through which a knife blade or other implement may be inserted into the receptacle for forcing the members apart, and a seal applied over the opening and slit to hermetically seal the box when closed, said seal being of substance through which the knife blade or other implement can readily be applied.

7. A receptacle comprising a body part and a cover part, each having a horizontal and a vertical wall, there being a rectangular opening through the vertical wall of the cover part within the edge thereof to keep the edge intact, the upper edge of which opening is adapted to appear opposite the upper edge of the body member when the receptacle is closed, thereby providing a thin slit through which a knife blade or other implement may be inserted into the receptacle for

forcing the members apart, and a seal in the form of a paster applied over the opening to prevent evaporation therethrough when the receptacle is closed.

8. In a receptacle comprising a body member and a cover member, an opening through one member having an edge appearing opposite an edge on the other member between which edges a suitable implement may be inserted to force the members apart, and inturned flanges for reinforcing the edges.

9. In a receptacle comprising a body member and a cover member, said members having telescoping walls, an opening through one wall having an edge disposed opposite an edge on the other wall whereby a suitable implement may be inserted between the opposite edges to force the members apart, and flanges extending inwardly from the edges and in engagement with each other.

10. In a receptacle comprising a body member and a cover member, said members having telescoping walls, an opening through one wall within the edge thereof to leave the edge intact, one edge of the opening being opposite an edge on the other wall, whereby a suitable implement may be inserted between the opposite edges to force the members apart, and reinforcing flanges extending inwardly from the edges.

In witness whereof, I hereunto subscribe my name this 8th day of January A. D., 1907.

CHARLES J. SCHMIDT.
